UNITED STATES PATENT OFFICE.

FREDERICK MANKEY, OF WILLIAMSPORT, PENNSYLVANIA.

DESIGN FOR A PANEL.

SPECIFICATION forming part of Design No. 16,231, dated September 8, 1885.

Application filed July 18, 1885. Term of patent 5 years.

To all whom it may concern:

Be it known that I, FREDERICK MANKEY, of Williamsport, Lycoming county, Pennsylvania, have invented and produced a new and 5 original Design for Panels, of which the following is a specification, reference being had to the accompanying photographs, forming part hereof.

Figure 1 represents my new design upon a 10 single panel. Figs. 2, 3, 4, and 5 represent panels formed by four smaller panels, each having the design of Fig. 1, but grouped together in different ways.

Similar letters of reference indicate like 15 parts.

Referring more particularly to Fig. 1, my 20 design consists of rows of pyramidal elevations disposed diagonally across the panel, with intervening channels or spaces of rectangular cross section. These elevations are as follows:

Beginning at the upper right-hand corner, (marked 1.) there are first two triangular elevations, A B, then a row of elevations, at the 25 ends of which are triangular elevations C D, and next inside these pyramidal elevations E F, mutilated by cutting at corresponding ends of both, but in oppositely-diagonal directions. Between the elevations E F are rectangular 30 elongated pyramidal elevations G H.

The following row of elevations has at one 35 end a triangular elevation, I, and next to it a mutilated pyramidal elevation, J, similar to E. At the opposite end of said row is an elevation, K, representing but one inclined side 40 of a pyramid. This forms the corner 2 of the panel. Next to this elevation K is a mutilated pyramidal elevation, L, and between elevation L and elevation J are rectangular elongated pyramidal elevations M N O P Q.

The next row of elevations has a triangular elevation, R, at one end, forming the corner 45 3 of the panel. At the other end is a triangular elevation, T, similar to A, and a mutilated pyramidal elevation, S, similar to L. Between the elevations S and R are elongated pyramidal elevations U V W X Y.

The next row of elevations has at each end a triangular elevation, Z, similar to A; next to

these, mutilated pyramidal elevations b c, similar to E F, and between these last is an elongated pyramidal elevation, d. Finally, the remaining corner 4 of the panel is formed by an elevation, e, similar to K. Between the rows of elevations, as described, are diagonal channels f g h i j, and between the several elevations are diagonal channels k l m n o p q r s.

The number of elongated pyramidal elevations such as M N O P Q in each row is not material, because with panels of different dimensions this number will necessarily vary.

By using four panels, each having the design shown in Fig. 1, and grouping them in different ways, I am enabled to produce composite panels of varied design. Thus in Fig. 65 2 four panels, as aforesaid, are placed together, so that their corners 3 shall meet. In Fig. 3 the same four panels are arranged with their corners 1 in juxtaposition. In Fig. 4 the corners 2 and in Fig. 3 the corners 4 are in contact. The result is a differently-appearing 70 central figure in each panel.

I claim—

1. The design for a panel, substantially as herein shown and described, which consists in 75 rows of complete and mutilated pyramidal elevations disposed diagonally across said panel, and formed and arranged as described, with intervening channels of rectangular section, the said elevations exhibiting on their surface a different grain marking from that appearing on the flat or bottom portion of said channels.

2. The design for a panel, substantially as described, and as represented in Fig. 1. 85

3. The design for a panel, substantially as described, and as represented in Fig. 2.

4. The design for a panel, substantially as described, and as represented in Fig. 3.

5. The design for a panel, substantially as 90 described, and as represented in Fig. 4.

6. The design for a panel, substantially as described, and as represented in Fig. 5.

FREDERICK MANKEY.
